(57) CLAIM

The ornamental design for a mobile beverage dispensary, as shown and described.

DESCRIPTION

FIG. 1 is a top front right perspective view of the mobile beverage dispensary;

FIG. 2 is a right plan view of the mobile beverage dispensary of FIG. 1;

FIG. 3 is a left plan view of the mobile beverage dispensary of FIG. 1;

FIG. 4 is a front plan view of the mobile beverage dispensary of FIG. 1;

FIG. 5 is a back plan view of the mobile beverage dispensary of FIG. 1;

FIG. 6 is a top plan view of the mobile beverage dispensary of FIG. 1; and,

FIG. 7 is a bottom plan view of the mobile beverage dispensary of FIG. 1.

The broken lines indicating signage, the interior of the mobile beverage dispensary, the wheels, certain external structures on the mobile beverage dispensary, and the undercarriage of the mobile beverage dispensary are environmental only and form no part of the claimed design.
